[57] CLAIM

The ornamental design for a buckle and strap assembly, substantially as shown and described.

DESCRIPTION

FIG. 1 is a side view of a buckle and strap assembly embodying my new design;

FIG. 2 is a top view thereof;

FIG. 3 is a bottom view thereof;

FIG. 4 is an end view taken from the left of FIG. 1;

FIG. 5 is an end view taken from the right of FIG. 1;

FIG. 6 is a sectional view taken in the direction of the arrows on line 6—6 of FIG. 2;

FIG. 7 is a section view taken on line 7—7 of FIG. 1;

FIG. 8 is a sectional view taken on line 8—8 of FIG. 1;

FIG. 9 is a perspective view thereof;

FIGS. 1, 2, 3, 6 and 9 are shown broken away to indicate indeterminate length.

FIG. 2

FIG. 3

FIG. 4 FIG. 5 FIG. 6 FIG. 7 FIG. 8

FIG. 6
